UNITED STATES PATENT OFFICE

AUGUST ROSENTHAL, OF MILWAUKEE, WISCONSIN, ASSIGNOR TO THE ROSENTHAL CORN HUSKING MACHINE COMPANY, OF SAME PLACE.

CORN HUSKING AND CUTTING MACHINE.

SPECIFICATION forming part of Letters Patent No. 639,615, dated December 19, 1899.

Application filed March 29, 1899. Serial No. 710,886. (No model.)

To all whom it may concern:

Be it known that I, AUGUST ROSENTHAL, of Milwaukee, in the county of Milwaukee and State of Wisconsin, have invented a new and useful Improvement in Corn Husking and Cutting Machines, of which the following is a description, reference being had to the accompanying drawings, which are a part of this specification.

10 My invention has relation to improvements in corn husking and cutting machines.

The object of the invention is the provision of rollers of such construction that the cutting mechanism is carried directly thereby, 15 in connection with a frame for supporting the rollers, said frame being so constructed and arranged as to permit the cornstalks to be fed longitudinally and to arrange themselves longitudinally on the rollers.

20 With the above primary object and other incidental objects in view the invention consists of the devices and parts or their equivalents, as hereinafter more fully set forth.

In the accompanying drawings, Figure 1 is 25 a side elevation of a machine embodying my invention. Fig. 2 is a transverse section of Fig. 1 on a plane through the cutting portions of the rollers. Fig. 3 is a detail plan view of the rollers. Fig. 4 is a cross-section through 30 the portions of the rollers where the separation and cutting is effected, the section being taken on a plane between two of the cutting-knives; and Fig. 5 is a view of a fragment of the shaft or axis of one of the rollers with 35 the clamping-collars which surround the shaft in section.

Referring to the drawings, the letter A indicates the base of the frame, B B the side boards, and C C the inclined side pieces of 40 the hopper. These side pieces extend longitudinally of the frame and their lower edges pass below and on the inner sides of the upper edges of the side boards B B, said lower edges converging towards the roller hereinafter 45 specifically described. Mounted in suitable bearings in the frame is a shaft D, the inner end of said shaft extending into a fan-casing F and having mounted on said inner end a fan F'. On the outer end of the shaft D is a 50 pulley E, around which a belt (not shown) may be passed for the purpose of imparting

rotation to the shaft D. The framework is on a gradual downward incline from the front end toward the rear, and the side boards B B have two oppositely-inclined bottom pieces 55 B' B'', the latter inclining toward the former and adapted to deposit material thereon, the said inclined bottom B' finally leading to an opening in the side of the fan-casing F.

The numerals 4 4' indicate shafts or axes for 60 the rollers. These shafts or axes are shown as provided with reduced ends or journals which are mounted in suitable yielding bearings in the frame of the machine.

One of the end journals of the shaft 4 is 65 shown as having mounted thereon a driving-pulley 5. The journals of the opposite ends of the shafts are provided with intermeshing gears 6 6'. By the arrangement described the shaft 4 and its roller are rotated in one direction by power applied to the band-pulley 5, and the shaft 4' and its roller are rotated in the opposite direction by the intermeshing gears 6, with the result that the two rollers are rotated toward each other. The rollers 70 are mounted in the framework of the machine so that the ends thereof where the pulley 5 is located constitute the forward ends. There is a gradual and equal declination of both rollers from these forward ends rearwardly. 75 The solid portions of the rollers, on which the husking is accomplished, are indicated by the numerals 7 7'. The remaining portions of the rollers are preferably made up of collars surrounding the shafts, the collars surrounding 80 the shaft 4 being indicated by the numeral 8 8' and the collars surrounding the shaft 4' by the numeral 8'. These collars are held in place by means of intersecting pins 9. The solid or husking portion 7 of one of the rollers is 85 provided with projecting husking-pins 10 and the solid husking portion 7' of the other roller with registering recesses 11 to receive said pins as the rollers revolve toward each other.

90 Clamped between the collars 8 of the shaft 4 are annular cutting-knives 12, which are arranged in series throughout the length of the separating and cutting portion of the roller of said shaft 4. The collars 8', surrounding 100 shaft 4', are spaced apart a slight distance to form grooves 13 to receive therein the cutting

edges of the knives, one side of each cutting-knife bearing against or in close proximity to one of the side bordering walls of a groove 13.

5 The several collars 8 are shown as provided with projecting conical nippers 14, there being preferably two of said nippers on each collar, arranged at diametrically opposite points thereof. Each of the collars 8' is provided with depressions or recesses 15, two of said depressions or recesses being also preferably provided for each collar and arranged at diametrically opposite points thereof.

In the operation of my invention the corn-stalks are fed horizontally and longitudinally between the side boards C of the trough and thence pass to and arrange themselves longitudinally on the rollers, with the butt-ends of the stalks at the forward ends of said rollers, the stalks settling in the angles of the two rollers. As the rollers revolve toward each other the knives act on the stalks and cut said stalks into fine pieces or shreds. By reason of the fact that the rollers are mounted 25 in yielding bearings the cut portions or shreds of the stalks are free to pass between the rollers and to fall on the inclined bottom pieces B' B² of the side boards B and thence slide down said bottom pieces and are finally 30 conducted by the bottom piece B' into the fan-casing, where they are acted upon by the fan within said casing and forced thereby through a conduit leading from the casing to the place of deposit. The knives by reason of their 35 contact with the side walls of the grooves 13 effect a shearing cut and are thereby rendered capable of effectually cutting the stalks in fine pieces. At certain periods of the rotation of the rollers the conical nippers are 40 brought into register with the depressions or recesses 15, and the portions of the stalks from which the ears extend are thereby necessarily pulled in between the point or edge of the nippers and the wall of the depressions 45 or recesses 15, and are thereby compelled to make a very short turn, the sharpened edges or points of the nippers at the same time pinching the stalks from the ears. The ears 50 of corn so severed are too large to work down 55 into the angle between the two rollers, so as to be affected by the shear cut of the cutting-knives, and hence the ears slide down the inclined rollers onto the husking portions of said rollers, where they are acted upon by the husking-pins and stripped of their husks.

So far as I am aware rollers have not heretofore been provided for a corn husking and cutting machine in which the separating of the stalks from the ears and the cutting of 60 the stalks and the husking of the ears, if desired, is accomplished as in my invention. This form of rollers presents a decided advantage, inasmuch as the necessity of separate shredding or cutting mechanism arranged 65 beneath the rollers or elsewhere is entirely avoided and simplicity and cheapness of construction in this class of machines thereby

greatly promoted. By my improved construction also much less power is required than in machines in which separate cutting mechanism is employed, inasmuch as in such class of machines separate driving mechanism for the cutting apparatus is necessary. With my arrangement but little power is required for causing the cutting-knives to operate, owing 70 to the pressure between the two rollers, and said rollers therefore are not required to be speeded to a great extent. In machines, however, in which separate cutting mechanism is employed a very high rate of speed for such 80 cutting mechanism is necessary.

While in the preceding description of my invention I have described certain details of construction, yet I do not wish to be understood as limiting myself thereto. For instance, it is not absolutely essential to my invention that the cutting-knives should be held between a series of collars and that a series of spaced collars should be provided on the other roller to form grooves to receive the 90 cutting-knives. The cutting-knives can be secured in any desirable manner, and the grooves on the other roller, if preferred, may be cut around or otherwise formed in said roller without departing from the spirit and 95 scope of my invention.

What I claim as my invention is—

1. In a corn husking and cutting machine, the combination, of a frame, shafts or axes mounted in bearings in said frame and arranged at a gradual downward incline from the front end of the machine to the rear thereof, rollers formed or provided on said shafts or axes, said rollers formed on their forward portions for a desired distance rearwardly 100 with coacting means for separating the ears from the stalks, and one of said rollers provided from its forward end rearwardly for a desired distance with a series of cutting-knives coacting with the other roller to effect 105 the cutting of the stalks, means for causing the rollers to rotate toward each other, and means for feeding the cornstalks so as to adapt them to arrange themselves longitudinally on the rollers.

2. In a corn husking and cutting machine, the combination, of a frame, shafts or axes mounted in bearings in said frame and arranged at a gradual downward incline from the front end of the machine to the rear thereof, rollers formed or provided on said shafts or axes, said rollers formed on their forward portions for a desired distance rearwardly 115 with coacting means for separating the ears from the stalks, and one of said rollers provided from its forward end rearwardly for a desired distance with a series of cutting-knives, and the corresponding portions of the other roller provided with a series of grooves 120 adapted to register with and receive the knives, and in connection with said knives to effect the cutting of the stalks, means for causing said rollers to revolve toward each other, and means for feeding the cornstalks 125

so as to adapt them to arrange themselves longitudinally on the rollers.

3. In a corn husking and cutting machine, the combination, of a frame, shafts or axes 5 mounted in bearings in said frame and arranged at a gradual downward incline from the frontend of the machine to the rear thereof, rollers formed or provided on said shafts or axes, said rollers provided from their forward portions for a desired distance rearwardly with coacting means for separating the ears from the stalks, and one of said rollers provided on its separating portions with a series of cutting-knives coacting with the 15 other roller to effect the cutting of the stalks, and both of said rollers provided with means for husking the ears of corn, said husking means being located on the portions of the rollers from the ends of the separating portions thereof to the rear ends of said rollers, means for causing the rollers to rotate toward each other, and means for feeding the cornstalks so as to adapt them to arrange themselves longitudinally on the rollers.
- 20 4. In a corn husking and cutting machine, the combination, of a frame, shafts or axes mounted in bearings in said frame and arranged at a gradual downward incline from the frontend of the machine to the rear thereof, 25 of, rollers formed or provided on said shafts or axes, one of said rollers provided for a desired distance from its front end toward the rear with nippers arranged at desired distances apart, and a corresponding portion of the other roller provided with depressions arranged at desired distances apart, and adapted 30 to receive the nippers as the rollers re-

volve, and one of said rollers also provided from its forward end rearwardly with a series of cutting-knives arranged at desired distances apart, and coacting with the other roller to effect the cutting of the stalks, means for causing the rollers to rotate toward each other, and means for feeding the cornstalks so as to adapt them to arrange themselves 45 longitudinally on the rollers.

5. In a corn husking and cutting machine the combination, of a frame, shafts or axes mounted in bearings in said frame, and arranged at a gradual downward incline from 50 the frontend of the machine to the rear thereof, rollers formed or provided on said shafts or axes, said rollers comprising separate collars surrounding the shafts or axes, the collars of one of the rollers formed or provided 55 with projecting nippers, and the collars of the other roller with depressions or recesses to receive the nippers as the rollers revolve, cutting-knives clamped between the collars of one of the rollers and adapted to extend 60 into the grooves between the collars on the other roller, and in connection with said grooves to effect a cut on the stalks, means for revolving the rollers toward each other, and means for feeding the cornstalks so as to 65 adapt them to arrange themselves longitudinally on the rollers.

In testimony whereof I affix my signature in presence of two witnesses.

AUGUST ROSENTHAL.
